UNITED STATES PATENT OFFICE.

THOMAS JAMES BURTON, OF MURPHYSBORO, ILLINOIS.

COVER FOR MANHOLES AND ANALOGOUS DEVICES.

Application filed June 26, 1922. Serial No. 571,066.

To all whom it may concern:

Be it known that I, THOMAS J. BURTON, a citizen of the United States, residing at Murphysboro, in the county of Jackson and State 5 of Illinois, have invented certain new and useful Improvements in Covers for Manholes and Analogous Devices; and I do declare the following to be a full, clear, and exact description of the invention, such as 10 will enable others skilled in the art to which it appertains to make and use the same.

This invention relates to an improved cover for manholes and analogous devices and the particular improvements therein re- 15 side in a means for locking the cover plate to the base ring or curb of the manhole or analogous device.

The improved locking means is mounted upon the unexposed side of the cover plate 20 but may be manually operated by means of a handle located on the exposed side of the plate. This handle is mounted so that it can be swung to an inoperative and out-of-the-way position and when in this position, it 25 is locked so that the locking means between the cover plate and the base ring or curb cannot be accidentally unlocked.

The cover plate is of such construction 30 that it may be made economically by molding or casting and the parts of the locking means are of simple construction so that very little machine work will be necessary in constructing the parts so that they can be assembled and fitted together. The device is 35 therefore of simple, strong, durable and inexpensive construction, which are highly desirable features in a device of this character.

The novelty of the invention resides in the various details of construction and the 40 combination and arrangement of parts which are hereinafter fully described and claimed and shown in the accompanying drawing.

In the accompanying drawing which forms a part of this specification:

45 Fig. 1 is a top plan view of a manhole base ring or curb and a cover plate therefor constructed so as to embody the principles of the present invention.

50 Fig. 2 is a central vertical sectional view through the base ring or curb and cover plate taken substantially on the plane indicated by the line 2—2 of Fig. 1 and illustrating the locking means in locked position and the operating handle in inoperative position.

Fig. 3 is a bottom view of the cover plate; 55 and

Fig. 4 is a central vertical sectional view of the cover plate, showing the operating handle for the locking means in operative position.

60 It is to be understood that the principles of the present invention may be embodied in connection with manholes, coalholes, cistern tops, water covers, gas meter covers, and analogous devices, but for illustrative 65 purposes, an embodiment in connection with a manhole cover has been selected.

In the illustrated embodiment of the invention, the numeral 1 designates the base ring or curb of a manhole. This is of the 70 usual construction, being cast in one piece, and is intended to be embedded in the earth, particularly in a street or road, so that its upper edge will be flush with the surface of the street or road. Formed integrally with 75 the base ring or curb 1 is a flange 2. This flange 2 is located a slight distance below the upper edge of the ring 1 and it projects inwardly therefrom so as to form an annular shoulder upon which a cover plate may rest. 80

In the drawing, the numeral 3 represents a cover plate which is constructed so as to rest upon the annular shoulder formed by the flange 2 of the base ring or curb 1. When the cover plate 3 is in place upon the ring 85 or curb 1, its upper side will be substantially flush with the upper edge of the ring or curb. The plate 3 is preferably made by casting or molding. Its central portion is of increased thickness and is provided with a 90 hole 4. If desired, the plate 3 may be reinforced by means of ribs 5 which extend radially from its central thickened portion to its edge. Depending from the lower side of the plate 3 at diametrically opposite points 95 are lugs 6 having holes 7 therein.

Mounted on the lower side of the plate 3 is an improved means for locking the latter to the base ring or curb 1. This means preferably consists of a bar 8, to the ends of 100 which are pivotally connected one of the ends of a pair of bolts 9. These bolts 9 pass through the holes 7 formed in the lugs 6 which depend from the lower side of the plate 3 and when projected, they have their 105 outer ends disposed beyond the flange 2 of the base ring or curb 1 so that they will prevent the cover plate 3 from being removed.

from the ring or curb 1. However, when the bolts 9 are retracted, the cover plate 3 can be removed from the base ring or curb 1. Retracting movement of the bolts 9 is effected by stop lugs 8' carried by the cover plate 3 and which are engageable by the bar 8. The projecting and retracting of the bolts 9 is effected by turning of the bar 8. In order to do this, the bar 8 is carried upon the lower end of a stem 10 which extends through hole 4 formed in the central portion of the plate 3. The upper end of the stem 10 carries a handle 11. This handle 11 is in the form of a loop or bail and is pivotally connected to the stem so that it can be extended longitudinally of the latter and also so that it can be extended laterally of the stem.

The upper side of the cover plate 3 is provided with a recess or groove 12 which is shaped to correspond with the shape of the handle 11 and which is located so that it will receive the latter when swung laterally with respect to the stem 10. Furthermore, the recess or groove 12 is located so that it will only receive the handle 11 when said handle is turned so that the bolts 9 are in their projected positions. By this means, the handle 11 when not in use will be disposed out of the way and at the same time it will be locked so that it cannot be turned and the bolts 9 accidentally retracted. When, however, it is desired to unlock the cover plate 3 from the base ring or curb 1, it is only necessary to swing the handle 11 upwardly so as to bring it longitudinally with respect to the stem 10, then to pull upwardly upon the handle until it is entirely withdrawn from the recess or groove 12 and finally to turn the handle so as to turn the bar 8 and retract the bolts 9. It will therefore be seen that the stem 10 is not only turnably mounted in the hole 4 in the cover plate 3, but is also slidably mounted in said hole.

From the foregoing description taken in connection with the accompanying drawing, it will be seen that the device is of very simple construction and can be made economically since very little if any machine work will be necessary in order to make its various parts properly fit together. Furthermore, it will be realized that the device is highly desirable because the locking

means is such that it may be easily operated 55 but when once locked, it cannot be accidentally unlocked.

Since various changes in form, proportion, and in the minor details of construction may be made without departing from 60 the principle or sacrificing any of the advantages of the invention, it is to be understood that such may be made within the meaning and scope of the appended claims.

What is claimed is:

1. A cover for manholes and analogous devices comprising a plate having a hole extending therethrough, locking means mounted on one side of said plate, a stem extending through said hole and turnably and slidably mounted therein, said stem being connected at one end to said locking means for operating the same, and a handle for turning said stem, said handle being pivotally connected to the other end of said 75 stem so as to be extended either on a plane of the axis of the latter or laterally thereof, said plate having its outer side provided with a recess for receiving said handle when swung laterally with respect to said stem, 80 said recess being located and constructed so as to prevent said handle and therefore said stem from turning until said handle is entirely removed out of said recess.

2. A cover for manholes and analogous 85 devices comprising a plate having a hole extending therethrough, locking means mounted upon the lower side of said plate, a stem extending through said hole and turnably and slidably mounted therein, 90 said stem being connected at its lower end to said locking means for operating the same, and a handle for turning said stem, said handle being pivotally connected to the upper end of said stem so as to be extended 95 either on a plane of the axis of the latter or laterally thereof, said plate being provided at its upper side with a groove for receiving said handle when swung laterally with respect to said stem, said groove 100 being shaped to conform to the shape of said handle and being located so as to prevent said handle and therefore said stem from turning until said handle is entirely removed from said groove.

In testimony whereof I have hereunto affixed my signature.

THOMAS JAMES BURTON.
